United States Patent Office

Des. 193,513
Patented Sept. 4, 1962

193,513

PRIVATE BRANCH EXCHANGE CONSOLE

Forrest P. Wight, Denville, N.J., assignor to Bell Telephone Laboratories Incorporated, New York, N.Y., a corporation of New York

Filed Oct. 10, 1961, Ser. No. 67,038

Term of patent 14 years

(Cl. D26—5)

FIG. 2

FIG. 1 is a perspective view of a private branch exchange console, showing my new design, the front and left side thereof being particularly shown; and

FIG. 2 is a perspective view of the console showing particularly the rear and right side thereof.

The essential features of my design reside in the portions shown in solid lines on the drawing.

I claim:

The ornamental design of a private branch exchange console, substantially as shown and described.
